UNITED STATES PATENT OFFICE.

HARRY E. HERSHHEY, OF WHITE WATER, KANSAS, AND GEORGE A. YANOCHOWSKI, OF CHICAGO, ILLINOIS, ASSIGNEES TO AUTOMATIC ELECTRIC COMPANY, OF CHICAGO, ILLINOIS, A CORPORATION OF ILLINOIS.

PARTY-LINE AUTOMATIC TELEPHONE SYSTEM.

1,287,992.

Specification of Letters Patent.

Patented Dec. 17, 1918.

Application filed November 28, 1913. Serial No. 803,524.

To all whom it may concern:

Be it known that we, HARRY E. HERSHHEY and GEORGE A. YANOCHOWSKI, both citizens of the United States of America, and residents of White Water, Butler county, Kansas, and Chicago, Cook county, Illinois, respectively, have invented certain new and useful Improvements in Party-Line Automatic Telephone Systems, of which the following is a specification.

Our invention relates to improvements in party-line automatic telephone systems, and has for its object the provision of improved means whereby one subscriber may call another subscriber on the same line. Heretofore, in party-line systems where provision has been made to permit one subscriber to call another on the same line, it has been necessary to remove the guarding potential from that line in order to permit the connector switch to call back on the calling line.

The object of our invention is to provide means for calling back on a line without necessitating the removal of the guarding potential in this manner.

This and other objects and features of our invention will be more readily understood by reference to the accompanying drawings, in which we have illustrated one specific embodiment of our invention in connection with a well-known form of automatic telephone system.

Figures 1 and 2 taken together show a complete connection between a calling substation A and a called substation A' in a telephone system embodying the principles of our invention.

The telephone system shown herein is an automatic system of the well-known type, in which the connections are established between the calling and called lines through the medium of subscribers' individual or line switches, selector switches and connector switches. The connection shown is established through the medium of the calling subscriber's line switch C, first selector E, second selector F, the connector H and the called subscriber's line switch C'. The line switch C is one of a group of similar switches which are controlled by a common mechanism or master switch D in such a manner that the plungers of all the idle line

terminal of an idle trunk line. At B there is shown a central office battery for supplying current for operating the switches and for talking purposes. At R a ringing current generator is shown and at Q a busy signaling machine is represented.

The system shown herein is also a party-line system--that is, there may be connected to each subscriber's line a plurality of substations similar to the substations A and A'. Any desired arrangement may be employed in order that the different stations on the same line may be signaled selectively. Very satisfactory results are obtained by the following well-known arrangement. The bells of the different substations are tuned or otherwise adapted to respond to only a certain kind of ringing current. At the central office means are provided for producing as many different kinds of ringing current as there are substations upon each line. Each line is accessible through as many different groups of connector switches as there are substations on the same, and each group of connectors is supplied with ringing current of different characters. Thus, to signal any particular substation on a line, it is necessary to call this line through the medium of a connector in a group which is supplied with ringing current of the proper character to operate the bell at the substation desired. Each of the different groups of connectors which have access to the same line may be accessible through different levels of the second selectors, so that the numbers of the different substations on each line may be different, and the proper group of connectors will be automatically selected when the number of any substation is called.

The automatic substations A and A' comprise the usual receiver 2, transmitter 3, ringer 4 and condenser 5. Being an automatic substation it is also provided with a suitable call-sending mechanism for controlling the automatic switches, which mechanism is represented diagrammatically by a pair of impulse springs 6 and 7 and an impulse wheel 8, which latter may be controlled in the well-known manner through the medium of a dial provided with finger holes in such a way that the impulse springs may be momentarily separated a number of

times, corresponding to the respective digits of the number of the called subscriber. A push button 9 is also provided by means of which the resistance 10 may be cut in series 5 with the receiver 2 and transmitter 3.

The line switches C and C' are of the general type of subscriber's switch shown in British patent to R. W. James No. 26,301 of 1906, resembling more closely, however, the 10 particular type shown in British patent to T. G. Martin No. 1419 of 1910. This line switch comprises, among other details, a plunger (not shown) attached to the end of a so-called plunger arm 21^a controlled by a 15 magnet 120. The magnet 120 comprises four windings, namely, a pull-down winding 30, a cut-off or holding winding 39, a line winding 20 and an auxiliary winding 40. The core of the magnet 120 is so constructed 20 that the magnetic circuit of the windings 20 and 40 is separate from that of the windings 30 and 39. The winding 30 operates both the plunger arm 21^a and the armature 21, while the winding 39 is only strong enough 25 to operate the cut-off armature 21 and to hold the plunger arm 21^a in its operated position after it has been operated. When the plunger arm 21^a is operated, the plunger is forced into the bank of contact springs, fore- 30 ing the springs 22, 23, 24 and 25 into engagement with the springs 26, 27, 28 and 29, respectively. Although only one set of springs (22-29) is shown, each line switch is provided with a plurality of such sets, 35 each set forming the terminal of a trunk line leading to a first selector switch E. Each trunk line is connected in multiple to the corresponding springs of all the line switches of the group which is controlled by 40 the master switch D. The switch C is controlled by the subscriber through the medium of the line relay 20, as will herein- after be more fully explained.

The master switch D is of the general type 45 of master switch shown in British Patent No. 26,301 of 1906, referred to above, being, however, of the particular type disclosed in British Patent No. 1419 of 1910, also referred to above. The function of the master 50 switch, as is well known, is to maintain the plungers of all the idle line switches in position to engage the terminal of an idle trunk line.

The first sector E is of the general type of 55 selector switch disclosed in United States Letters Patent No. 815,321, granted March 13, 1906, to Keith, Erickson and Erickson except that the so-called side switch is omitted, in the manner shown in British patent to 60 T. G. Martin No. 10,376 of 1912. Among other details, the selector E comprises a bank of contacts arranged in horizontal rows or levels, which contacts are adapted to be engaged by a set of wipers 68, 69 and 70 car-

ried upon a shaft (not shown) which has a 65 vertical movement controlled by the vertical magnet 53 and a rotary movement controlled by the rotary magnet 61. The operations of the switch are controlled through the medium of the double-wound line relay 31. 70 Means for permitting the switch to be restored to normal position are provided in the release magnet 114, which, upon energizing, withdraws the retaining pawls from the shaft. The spring contacts 54 and 55 75 are permitted to close only when the switch shaft has been raised one or more steps from its lowest position. The relays 37 and 52 are slow acting relays—that is, they deenergize slowly after their energizing circuits 80 are broken.

The connector switch H is of the general type of connector switch disclosed in United States Letters Patent No. 815,176, granted March 13, 1906, to Keith, Erickson and 85 Erickson, the circuits being modified, however, to adapt the switch to operate in a system in which the central office apparatus is controlled by impulses delivered over the two sides of the line in series, in the manner 90 shown in British Patent No. 1419 of 1910, above referred to. Like the selectors, the connector is provided with a shaft (not shown) carrying the wipers 96, 97 and 98, which shaft is controlled by the vertical 95 magnet 94 and the rotary magnet 102. The usual side switch comprising the wipers 95, 103, 104 and 105 is controlled by the private magnet 99 in the usual and well-known manner. The magnet 113 is the usual release 100 magnet. The line relay 79 and the slow acting relay 80 provide the calling line with talking current, and the so-called back-bridge relay 109 supplies the called line with talking current. The application of ringing 105 current to the called line is controlled by the ringer relay 107. At Q there is shown a 'busy signaling' machine, the function of which is to send, under certain conditions, a busy tone back over the line. A second 110 ringing relay 127 is likewise provided for sending ringing current back over the calling line when a subscriber is calling another subscriber on the same line. The busy signaling machine, as represented herein, comprises an induction coil or transformer the primary winding of which is included in a local circuit with a battery and an interrupter of high frequency. Through the medium of this interrupter an interrupted 120 current is supplied to the primary winding which induces an alternating current in the secondary winding, whereby, when said winding is connected with the subscriber's line, a buzzing sound is heard in his receiver. Although there is shown a plurality of ringing current generators R associated with the connector H, it will be un-

derstood that they may be one and the same generator. The same is true in regard to the interrupting devices 106.

A general description of the apparatus having been given, it will now be explained how connection can be established between the line of substation A and the line of the substation A'. The number of the calling line we will assume to be 2133 and the number of the called line 2222. Since the automatic switching apparatus disclosed herein is in general well known in the art, and is described in the publications herein referred to, its operation will be explained in a more or less general manner. Upon the removal of the receiver from the switch-hook at the substation A preparatory to making a call, an energizing circuit is closed through the line winding 20 of the individual switch C, the circuit being as follows: from ground G through the springs 14 and 15, conductor 16, through the substation A, conductor 17, through the springs 18 and 19 and the winding 20 to battery B. The winding 20, upon being energized, closes a circuit through the pull-down winding 30 in series with the auxiliary winding 40. The pull-down coil, upon energizing, attracts the plunger arm 21^a, thereby operating to close circuits through the bank of springs 22 to 29, inclusive. It also operates the cut-off armature 21, thereby disconnecting the line winding 20 from the line. The armature 41 does not fall back immediately, however, owing to the fact that the winding 40 is still in series with the pull-down winding 30. Upon the plunger arm 21^a being attracted, the springs 42 and 43 are brought together to short-circuit the auxiliary winding 40, thus permitting the armature 41 to fall back. This slow action of the armature 41 allows sufficient time for a holding circuit to be closed in the switch ahead for the cut-off or holding winding 39. The engagement of the springs 22 and 25 with the springs 26 and 29, respectively, extends the subscribers' lines to the line relay 31 of the selector E. The line relay 31 of the selector E is therupon energized through a circuit from ground G² through the lower winding of the line relay 31, springs 33 and 32 of the relay 34, through the springs 29 and 25 to the conductor 16, through the substation A to the conductor 17, through the springs 22 and 26, through the springs 35 and 36 and the upper winding of the line relay 31 to battery B.

The line relay 31, upon becoming energized, closes a circuit through the slow acting relay 37, this circuit extends from ground G² through the spring 49 and its front contact, from ground G² through the springs 38, springs 27 and 23 and through the holding winding 39 of the line switch C to battery B. The winding

39, upon energizing, holds the armature 21 and plunger arm 21^a in their operated positions after the circuit of the pull-down winding 30 is broken by the falling back of the line armature 41. From the same point G² 70 a guarding potential is supplied to the connector private bank contacts of the calling line by way of the conductor 44. This circuit extends over the circuit just traced to the bank spring 25, thence over the normal 75 conductor 44 to said private bank contact. The energization of the relay 37 also prepares a circuit for the vertical magnet by bringing the springs 45 and 46 into engagement, and opens the circuit of the release 80 magnet 114 at the springs 46 and 47.

The calling subscriber now operates his calling device for the first digit 2 of the called number, whereby the substation impulse springs 6 and 7 are separated twice 85 momentarily, each time breaking the circuit of the selector line relay 31. The relay 37 of the selector being slow acting does not deenergize during the momentary interruptions of its circuit by the relay 31, and consequently each time the latter relay deenergizes, an impulse is transmitted over the circuit extending from ground G² through the springs 49 and 48, 50 and 51, 46 and 45, relay 52 and the vertical magnet 53 to battery B. The vertical magnet, receives two impulses over this circuit and operates to raise the switch shaft and wipers two steps to a position opposite the second row or level of bank contacts and at the same time the shaft-controlled contacts 54 and 55 are closed. The slow acting relay 52 is maintained in its energized position continuously while impulses are being transmitted to the vertical magnet and, in its energized position, closes a circuit extending from ground G² at the relay 37, 100 through the springs 56 and 57 and the relay 58 to battery B. The relay 58, upon energizing, forms a locking circuit for itself extending from ground G² at the relay 37, 105 through the springs 38, springs 59 (which are controlled by the rotary magnet 61), off-normal springs 55, springs 63 and 62 and the relay 58 to battery B. Thus, upon the deenergization of the relay 52 after the last 110 impulse is delivered to the vertical magnet, the relay 58 remains energized and the circuit of the rotary magnet 61 is closed, which circuit extends from ground G² through the springs 38, 59, 55, 63 and 62, 57 and 65, 66 115 and the magnet 61 to battery B. The magnet 61, upon energizing, rotates the wipers one step and, by opening the spring contacts 66 and 59, disconnects ground G² from itself and from the relay 58. If the first trunk 120 line of the second level is idle, the relay 58 deenergizes as soon as the spring contact 59 is opened. If this trunk line is busy, however, the private wiper 69 finds the contact it engages provided with a guarding 125

ground potential which is transmitted to the relay 58 through its springs 63 and 62 and thereby prevents it from deenergizing. The magnet 61, however, deenergizes when the 5 spring contact 66 is broken, regardless of whether the relay 58 remains energized or not. If the relay 58 remains energized, the circuit of the rotary magnet will be again closed as soon as its armature drops back far 10 enough to close the contacts 66 and 59. The rotary magnet will, therefore, operate in a manner similar to that of a buzzer to advance the wipers step by step over the contacts until the non-grounded contact of an 15 idle trunk line is reached by the wiper 69, whereupon the relay 58 deenergizes. The relay 58, upon deenergizing, whether after one or several operations of the rotary magnet, permanently breaks the circuit of the 20 magnet 61 and closes the circuit of the switching relay 34, which circuit extends from ground G² through the springs 38, 59 and 55, 63 and 64 and the relay 34 to main battery B. The relay 34, upon energizing, 25 disconnects the line relay 31 from the line and extends the line connection over the heavy conductors shown, through the wipers 68 and 70 to the second selector F. The line relay 71 of the switch F thereupon be- 30 comes energized and closes the circuit of the relay 72, which in turn, upon energizing, completes a circuit extending from ground G², spring 74, wiper 69 of the switch E, springs 63 and 64 and the relay 34 to bat- 35 tery B. This circuit maintains the relay 34 energized after its origin energizing circuit is broken by the relay 37, which deenergizes shortly after the line relay 31 is disconnected from the line. A circuit is also formed from 40 the private wiper 69 of the selector F, springs 55, 59, springs 27 and 23 and the holding coil 39 of the line switch C to bat- 45 tery B and also from the spring 23 through the conductor 44 to the connector private bank contact associated with the line 50 switch C. This circuit keeps the holding coil 39 of the line switch C energized and also keeps a guarding potential upon the connector private bank contact associated with the line 55 switch C. In addition, the relay 72 of the selector F also maintains a guarding ground potential upon the private bank contacts of the trunk line in the banks of the first selector switches E which have access to said trunk line.

When the substation calling device is operated for the second digit 2, the selector F operates in the same manner as explained for the selector E to extend the connection 60 over the trunk conductors 75, 76 and 77 to the connector H. The line relay 79 of the connector thereupon becomes energized over the following circuit: from ground G² through the line relay 79, over the heavy 65 conductor to and through the substation A

and over the other heavy conductor through the slow acting relay 80 to battery B. The slow acting relay 80, upon becoming energized, provides a holding circuit for the relays 78, 34 and 39 of the switches F, E and C, respectively. This circuit extends from ground G² through the springs 81, conductor 77, springs 83 and 84 and the relay 78 to battery B and also through the contacts 85, contacts 86, wiper 69 of the selector E, springs 63 and 64 and the relay 34 to battery B, and also through the contacts 55, contacts 59, springs 27 and 23, through the holding winding 39 to battery B, as well as through the conductor 44 to place a guarding potential 70 upon the private bank contact of the substation A. The energization of the line relay 79 closes a circuit through the slow acting relay 87, which relay, upon energizing, prepares the circuit of the vertical magnet 75 and at the same time opens the release magnet circuit.

When the substation calling device is operated for the third digit 2, the circuit of the connector line relay 79 is broken twice. 90 Since the relay 80 is slow acting it does not deenergize during the momentary interruptions of its circuit. For the same reason the relay 87 remains energized during the momentary interruptions of its circuit by 95 the line relay 79, so that each time the latter relay is deenergized, a circuit is closed extending from ground G² through the springs 85 and 88, springs 91 and 90, relay 93, vertical magnet 94 and the side switch 100 wiper 95 (in first position) to battery B. The vertical magnet 94 receives two im- 105 pulses over this circuit and operates to raise the switch wipers 96, 97 and 98 to a position opposite the second level of bank contacts. The relay 93, which is included in series with the vertical magnet, remains in its energized position during the entire time that impulses are being transmitted through it and operates to close the circuit of the 110 private magnet 99. The circuit for the pri- 115 vate magnet extends from ground G² through the springs 101 and 100 and the private mag- net 99 to battery B. After the last impulse is delivered, the relay 93 opens the circuit of the private magnet 99, which, upon deener- 120 gizing, permits the side switch to advance from first to second position. The movement of the side switch wiper 95 from first to second position transfers the battery connection 125 from the vertical magnet 94 to the rotary mag- net 102. The calling subscriber now operates his calling device for the last digit 2, in re- 130 sponse to which the connector line relay op- erates to transmit two impulses through the rotary magnet 102 in series with the relay 93, whereby the shaft wipers are rotated onto the contacts of the desired line. This circuit extends from ground G², springs 89 and 88, springs 91 and 90, relay 93, springs 130

133, rotary magnet 102 and the side switch wiper 95 (in second position) to battery B. The relay 98 operates in response to the impulses for this digit in the same manner as for the previous digit to cause the private magnet 99 to advance the side switch to third position. By the engagement of the side switch wipers 103 and 104 with their third-position contact points, the line connection is completed with the called line. Upon the engagement of the wiper 105 with its third-position contact point, a circuit is completed through the cut-off winding 39' of the called line switch. The circuit extends from ground G¹⁰, side switch wiper 105 (in third position), private wiper 97 and the cut-off winding 39' to battery B. The cut-off winding of the called line switch, upon energizing, operates to disconnect the line 20 relay 20' from the called substation. The connection of ground G¹⁰ with the connector private bank contact of the called line prevents the called line from being seized by some other connector switch. By the 25 engagement of the side switch wiper 95 with its third-position contact point, the circuit of the ringer relay 107 is closed. This circuit extends from ground G¹¹ through the interrupter 106, ringer relay 107 and the 30 springs 108 and the side switch wiper 95 (in third position) to battery B. The ringing relay disconnects the calling line from the called line and bridges the ringing current generator R across the called line to 35 signal the called subscriber. The ringing relay is energized only intermittently through the medium of the interrupter 106. Upon the response of the called subscriber his line is provided with talking current 40 through the windings of the back-bridge relay 109, which relay, upon energizing, closes the circuit through the ringer cut-off relay 110. The said circuit extends from ground G¹⁰ through the side switch wiper 45 105 (in third position), springs 111 and the ringer cut-off relay 110 to battery B. The relay 110, upon energizing, interrupts the circuit of the ringing relay 107 at the 50 springs 108 and closes a locking circuit for itself through the springs 112, independent of the springs 111.

After the conversation is completed, the connection is released by the hanging up of the receiver at the calling substation in the 55 usual manner.

It having been explained how one subscriber establishes connection with another subscriber and releases the same, it will now be explained how a connection is prevented 60 from being made with a busy line. If the called number is busy, there will be a guarding potential upon the connector private bank contact, just as explained in connection with the line switch C. The connector 65 private wiper 97, upon engaging this guard-

ing contact, closes a circuit from ground at the private bank contact through the private wiper 97, side switch wiper 105 (in second position), springs 116 and 115, busy relay 117, springs 118 and 100 and the private 70 magnet 99 to battery B. The busy relay 117, upon energizing, closes the contact of springs 119 and a busy tone is sent back to the calling subscriber from the busy machine Q by way of the side switch wiper 104 75 (in second position), thence to the calling substation to battery B, whereupon the receiver is replaced on the switch-hook and the connector is released in practically the same manner as described above. 80

It will now be explained how the substation A can call the substation 2233, the said substation being on the same line as the substation A. The second digit of the number 2233 being 2 indicates that the bells of substation 2233 are designed to be rung from the same group of connectors as were used in calling the substation 2222. The subscriber at substation A removes his receiver and calls the digits 2-2-2-3 in the same 90 manner and with the same results as explained for the number 2222, except that now the wipers of the connectors H are resting upon the bank contacts 121, 122 and 123, which are the connector bank terminals of the line switch C. Of course the private bank terminal 122 will be grounded, as above explained, and this will cause the connector H to throw the busy tone back to the substation A, but the subscriber at substation A, knowing that he is calling a party upon his own line, disregards the busy signal and presses the button 9, thereby cutting the high resistance 10 in series with his receiver and transmitter. This added resistance in the line circuit so reduces the flow of current through the relays 79 and 80 that the relay 80 falls back until the springs 124, 125, and 126 are in contact. The springs 81 also remain in contact at this time. The 100 spring 126 is a heavy spring and adjusted with stiff tension, while the springs 124 and 81 are weak. The relay 79 falls back until the spring 88 makes contact with the spring 89. This opens the circuit of the relay 87, 115 which, upon deenergizing, causes the release of the connector switch H in the manner previously explained. When the springs 124, 125 and 126 of the relay 80 are in engagement, a circuit is closed from ground 120 G¹¹, interrupter 106, auxiliary ringing relay 127 and the springs 125, 126 and 124 to battery B. It will be seen that when the relay 80 first pulls up, the springs 124, 125 and 126 are in contact too short a time for 125 the relay 127 to energize, but upon their coming into contact, as above explained, the circuit through the auxiliary ringing relay 127 causes it to be energized intermittently, thus cutting off the relays 79 and 80 and 130

throwing current from the generator R out upon the line A to ring the bell of substation 2233. The energization of the relay 127 also closes the springs 128, which places 5 ground G¹² upon the release trunk to take the place of ground G⁸, which is taken off an instant later by the deenergization of the relay 80, when the line circuit is opened at the springs 129, 130, 131, and 132. The 10 springs 129 and 131 are adjusted to make contact with the springs 130 and 132, respectively, upon the deenergization of the relay 127, before the springs 128 break contact, thus insuring that ground G⁸ is again 15 placed upon the release trunk before ground G¹¹ is removed. The subscriber at substation A will hear the ringing current projected upon his line through his receiver 2 in series with the transmitter 3 and high 20 resistance 10. In this way he will be advised that the called subscriber is being rung and the cessation of the ringing current will inform him that the called subscriber has answered, whereupon he will release the button 9 and converse with the subscriber at 25 substation 2233 in the usual manner. The removal of the receiver at the substation 2233 bridges the receiver and transmitter directly across the line and this increases the 30 flow of current to such an extent that the relay 80 again entirely energizes and opens the circuit of the auxiliary ringing relay 127 at the springs 124, 125 and 126. The relay 79 again also energizes and upon doing so closes the circuit of the relay 87, 35 which is without effect at this time. Upon completion of the conversation, the last subscriber to hang up opens the circuit of the relays 79 and 80. The deenergization of the relay 79 opens the circuit of the relay 87, which is without effect at this time. The deenergization of the relay 80 removes the ground G⁸ from the release trunk and effects the release of the selectors E and F 40 and of the line switch C in the same manner as described above.

It will thus be seen that we have devised a very efficient system in which one party can call back on the same line without necessitating the removal of the guarding potential from that line. In other words, the guarding potential for the line is maintained at all times to prevent a subscriber on another line from obtaining connection with 55 that line, and yet the calling party is enabled to ring back on his line in order to signal the desired called subscriber located on the same line.

While we have illustrated a specific embodiment of our invention in connection with one specific form of automatic telephone system, it will, of course, be understood that various changes and modifications will readily suggest themselves to those skilled in the art, and that our invention is

equally as well adapted for use in connection with various other forms of automatic or semi-automatic telephone exchange systems.

What we claim as our invention is:—

1. In a telephone system, a party-line, a connector switch, means for extending a connection from said line to said connector switch, means for placing a guarding potential on said line when a call is initiated, and 70 means for operating said connector to seize said line and to automatically signal a second station on said line without removing said guarding potential.

2. In a telephone system, a calling and a 80 called line, a connector switch, a progressively movable wiper for said switch, and means in said connector switch for automatically applying ringing current to said calling line over a circuit excluding said wiper, 85 and to said called line over said wiper.

3. In a telephone system, a subscriber's line, a connector switch, means including a trunk line for extending a connection from said line to said switch, and a ringing relay 90 for separating said trunk from said connector.

4. In a telephone system, an automatic progressively movable switch, a line terminating in said switch, a set of wipers for 95 said switch for extending connection therewith, a signaling relay in said switch associated with said line for projecting signaling current over said line, and a signaling relay in said switch associated with said 100 wipers for projecting signaling current over said wipers.

5. In a telephone system, a line, an automatic progressively movable switch, line terminals associated with said switch, wipers 105 associated with said terminals, means for operating said switch to move said wipers into engagement with said terminals, release equipment for disconnecting said wipers from said terminals after the connection is 110 made, a signal for said line, a source of signaling current, and a signaling relay for said connector for projecting signaling current to said line after the switch has released, to operate said signal.

6. In a telephone system, a line, an automatic progressively movable switch, line terminals associated with said switch, wipers associated with said terminals, operating magnets for said switch to move said wipers 120 into engagement with said terminals, a release magnet for disconnecting said wipers from said terminals after the connection is made, a signal for said line, a source of signaling current, and a signaling relay for said 125 connector for projecting signaling current to said line after the switch has released, to operate said signal.

7. In a telephone system, a line, a calling terminal for said line, a terminal for calling 130

said line, an automatic trunking switch, means for connecting the line with the switch via said first terminal and for operating said switch to find the terminal for calling said line, a signal for said line and a signal controlling relay in said switch for operating said signal, a busy test circuit for said line, means for applying a busy potential to said circuit when the line and the switch are connected and for maintaining said potential applied to said busy test circuit until after the signal is operated.

8. In a telephone system, a line, a busy test circuit for said line, a calling terminal for said line, a terminal for calling said line, an automatic progressively movable switch for finding the terminal for calling said line, means for applying a guarding potential to said busy test circuit via said first terminal before said second terminal is found and for maintaining said potential applied thereto, a signal for said line, means for applying signaling current to said line for operating said signal after the terminal is found and without removing the potential from the test circuit.

9. In a telephone system, a line, a terminal for said line for calling from said line, a terminal for said line for calling said line, a signal for said line, an automatic progressively movable switch for finding said second terminal and for signaling the line by projecting signaling current to the line by way of the terminal for calling from said line.

10. In a telephone system, a line, a terminal for said line for calling therefrom, a terminal for said line for calling thereto, a signal for said line, an automatic progressively movable switch for said line for finding the said second terminal, a source of signaling current associated with said switch, a signaling current circuit controlled by said switch for projecting signaling current to the line from said source to operate said signal via said first terminal.

11. In a telephone system, a line, a terminal for said line for calling therefrom, a terminal for said line for calling thereto, an automatic switching apparatus located between said terminals, said switching apparatus under the control of the line for bridging said switching apparatus between the two terminals, a signal for said line, a source of signaling current associated with said automatic switching apparatus controlled from the line through said switching apparatus to direct signaling current to the line by way of the said first terminal for operating said signal.

12. In a telephone system, a line, a terminal for said line for calling therefrom, a terminal for said line for calling thereto, an automatic switching apparatus located between said terminals, said switching appa-

ratus under the control of the line for bridging said switching apparatus between the two terminals, releasing mechanism for said switching apparatus, automatically controlled to release said switching apparatus when the bridge is completed, a signal for said line, a source of signaling current associated with said automatic switching apparatus controlled from the line through said switching apparatus to direct signaling current to the line by way of the said first terminal for operating said signal, after the switching apparatus is released.

13. In a telephone system, a line, a branch for said line for calling therefrom, a branch for said line for calling thereto, automatic switching apparatus located between said branches, said switching apparatus under the control of the line for bridging said switching apparatus between the two branches, a signal for said line, a plurality of sources of signaling current associated with said automatic switching apparatus, means for selecting one of said sources of signaling current, said selected signaling current controlled from the line through said switching apparatus to direct signaling current to the line from the selected source by way of the said first terminal for operating said signal.

14. In a telephone system, a plurality of lines, means including an automatic switch for connecting a calling one of said lines with a called one of said lines, separate ringing relays in said switch for signaling the called line, means for bringing one of said relays into use when the called line is also the calling line, and means for bringing the other of said relays into use when the called line is not the calling line.

15. In a telephone system, a plurality of lines, a connecting link for uniting any two of said lines in conversation, fixed and movable terminals at opposite ends of said link, means for connecting a calling line with said fixed terminals, a source of signaling current, means for connecting said source with the called line via said fixed terminals if the called line is also the calling line, and means for connecting said source with the called line via said movable terminals if the called line is not the calling line.

16. In a telephone system, a plurality of lines, a connecting link circuit, a set of terminals at one end of said link for connection to calling lines, a set of terminals at the other end of said link for connection to called lines, means for connecting a calling line with said first set of terminals, a source of signaling current, and means controlled over the calling line for connecting said source with either set of terminals to the exclusion of the other set.

17. In a telephone system, a plurality of lines, a connecting link circuit, means for

- 3
- connecting said link at one end to calling lines, means for connecting said link at the other end to called lines, a source of ringing current, ringing switches in said link for connecting said source to either end thereof, and means whereby said switches are controlled over a connected calling line.
18. In a telephone system, a subscriber's line, an automatic switch, a second subscriber's line accessible to said switch, means for extending said first line to said switch, a source of ringing current, and devices controllable by the subscriber on said first line at his option for operating said switch to connect with said second line or for connecting said source with the said first line without operating said switch.
19. In a telephone system, a trunk line terminating in an automatic switch, a called line accessible to said switch, a calling line, means for extending said calling line to said trunk line, means controllable over the calling line for operating said switch to connect with the called line, a source of ringing current, and means controllable over the calling line for connecting said source with said trunk line without operating said switch.
20. In a telephone system, a subscriber's line, a connector switch, means including a trunk line for extending said line to said switch, other subscribers' lines accessible to said switch, a source of ringing current, and means in said connector switch controllable by a subscriber on the said first line for connecting said source with said trunk line to signal a second subscriber on said first line.
21. In a telephone system, an automatic connector switch, a calling line and means for extending the same to said switch, a plurality of fixed called line terminals in said switch, one of said terminals being associated with the said calling line, a movable terminal in said switch operable to connect with any of said fixed terminals, a source of ringing current, means for connecting said source with a called line by way of said movable and fixed terminals, means for preventing such connection if the called line is also the calling line, and means for then connecting said source with the said calling line direct.
22. In a telephone system, an automatic connector switch, a calling line and means for extending the same to said switch, a plurality of other lines having fixed terminals
- in said switch, a movable terminal in said switch controllable over the said calling line to connect with any of said fixed terminals, a source of ringing current, and means for connecting said source with the said calling line independent of said movable terminals.
23. In a telephone system, a calling and a called line, a connector switch, means for connecting said calling line with said connector switch, and for operating said connector switch to connect with the called line, means in said connector switch for automatically applying ringing current to said called line and for then releasing said switch and applying ringing current to the calling line without releasing the said connection to said switch.
24. In a telephone system, a calling and a called line, an automatic connector switch for establishing a connection between said lines, a pair of line relays for said switch, means controlled by one of said relays to operate said switch to seize a called line and automatically apply ringing current thereto, and means controlled by the other line relay for releasing said connector switch.
25. In a telephone system, a calling and a called line, a connector switch, means for connecting said calling line with said connector switch and for operating said connector switch to connect with the calling line, means in said connector switch for automatically applying ringing current to said called line, and means controlled over the calling line to release said connector switch and to apply ringing current to the calling line over said connection to the connector switch.
26. In a telephone system, a calling and a called line, a source of ringing current, a plurality of automatic switches, means for operating said automatic switches to connect said calling and called lines and to automatically apply said source of ringing current to the called line, and means controlled over said calling line to release only one of said switches and to automatically apply ringing current to said calling line.

Signed by us at Chicago, Cook county, Illinois, this 13th day of November, 1913.

HARRY E. HERSHEY.

GEORGE A. YANOCHEWSKI.
